UNITED STATES PATENT OFFICE.

EMMA SIEBERT, NÉE RÜPRICH, MARTHA SIEBERT, AND ALBERT SIEBERT, OF MAGDEBURG, GERMANY.

LAST.

Application filed February 11, 1925, Serial No. 8,569, and in Germany February 20, 1924.

Boots made on the commonly used lasts have the inconvenience that they are tread down on the outer side as the foot has the tendency to move beyond the edge of the sole. As the foot is held at the rear by the stiff heel cap this treading down proves that the shape of the last is not correct. In a boot which has been used some time the centre line of the sole of the foot does generally 5 no longer coincide with the centre line of the sole of the last, wherefrom results a regular wearing of the boot sole and of the heel.

It has been proposed to avoid this by giving to the last a special shape so that the centre line of the last in the rear part forms an angle with the centre line of the fore-part. In the lasts of known type the point of intersection between the centre line of 10 the rear part and the centre line of the fore-part is wrongly situated, e. g. too far advanced, in proximity of the ball. The angle between the two centre lines is further sometimes too acute.

25 The present invention is based on the knowledge that the point of intersection of the centre line of the rear part of the last and of the centre line of the fore-part of the last must be situated in the last third 30 at the rear of the last and the angle formed by the two centre lines must be of about 10°. It is further important that the cross section of the rear part of the last be different from the commonly used cross section in 35 order to more uniformly distribute the mass of the wood at either side of the centre line.

On the accompanying drawing:—

40 Figs. 1 and 2 illustrate the theoretical principle for the selection of this point of intersection with the aid of the bony structure of a foot shown in plan view.

Fig. 3 is a cross section through the rear part of the last on line *a—a* of Fig. 4, the center line of the commonly used shape of 45 the last being shown in dash line and the shape of the last improved according to the invention being shown in full lines.

Fig. 4 is a plan view of the last sole according to this invention.

50 Fig. 5 shows a plan of a last built over this fundamental form and the last wedge.

The actually used theory considers the bony structure of the foot as an arch which bears on the ground at the heel and at the 55 ball, it being supposed that the foot moves

along a line which connects approximately the centre of the big toe with the centre of the heel. This walking line moreover forms the basis of the theoretical construction of boots. The action of the bony structure of the foot is however in reality not so simple as the foot executes lever-like actions.

The one of these levers is indicated in Fig. 1 and the other in Fig. 2.

The tibia rests upon the talus 1 at the side 65 which is in Fig. 1 at the right. The talus is supported by the scapha 2, the three wedge-bones 3 and the three metacarpal bones 4 of the half of the foot situated on the inner side. On the three metacarpal 70 bones follow the three toes the bones of which do however intervene very little to support the weight of the body. The three wedge bones 3 and the three metacarpal bones 4 form a transverse arch which is supported by the second lever (Fig. 2).

This second lever which forms a longitudinal arch is composed of the heel bone 5, the cuboid bone 6 and the two outer metacarpal bones 7 on which follow again the 80 toes. The talus 1 rests, as can be seen from Fig. 2, upon the heel bone. The rear part of the heel bone bears upon the sole and carries the talus. The outer lever (Fig. 2) prevents in this manner the giving way of the arched inner lever (Fig. 1). In order to enable this propping the outer lever must be pressed against the inner lever and sit upon the ground as straight as possible. The shape of the rear part of the boot must 85 approximately correspond with the position and formation of the heel bone in order to give the correct support. This means that the rear part of the last must stand, with regard to the forepart, at an angle of approximately 10° and the apex of this angle must be a point which is situated above the talus. The angle must be outwardly directed.

Herefrom results the fundamental shape 100 of the sole of the last shown in Fig. 4. The front centre line 9 of sole 8, said line having been obtained by bisecting the cross lines, is outwardly inclined so that at the point M the centre line 10 of the rear part 105 of the last and the prolongation of the centre line 9, enclose an angle of approximately 10°. On the inner side of the boot an outward bulging 11 and on the outer side of the same a hollowing 12 are formed which 110

must remain visible when the last is being made.

Fig. 5 shows the last 13 built over this fundamental shape and the last wedge 14. In Fig. 5 the centre line 9 forms with the centre line 10 of the rear part an angle of 10°. The two centre lines intersect at the point *m* above the talus. This point *m* is situated approximately at the beginning of the last third of the length of the last, counted from the toes.

The cross section of the last must also be somewhat different from the commonly used cross section. The cross section has hitherto, as shown in Fig. 3 in dash line, been convex at the inner side and concave at the outer side so that the greater portion of the mass of the wood is on the inner side of the centre line 10. In order to obtain a position of the heel resembling the foot position the wood must however be uniformly distributed at either side of the centre line, as shown in Fig. 3 in full line. On the inner side must be a cavity and on the outer side a bulged out part, which is

just contrary to the shape of the commonly used lasts.

We claim:—

1. A last for boots in which the rear part stands in outward direction at an angle 30 to the fore-part having the centre line of the rear part located so that it forms with the centre line of the fore-part an angle of approximately 10° and so that it intersects this centre line of the fore-part at a 35 point which is situated approximately at the beginning of the last third of the length of the last counted from the toes.

2. A last for boots having its heel so shaped that the mass of the wood is uniformly distributed at either side of the centre line, the inner side of the heel part being concave and the outer side being convex.

In testimony whereof we affix our signatures.
